UNITED STATES PATENT OFFICE

154,857

DESIGN FOR A COMBINED CIGARETTE HOLDER AND ASH TRAY

Carl G. Johnson, Rochester, N. Y.

Application April 25, 1946, Serial No. 134,354

Term of patent 7 years

(Cl. D85—8)

To all whom it may concern:

Be it known that I, Carl G. Johnson, a citizen of the United States of America, residing at Rochester, in the county of Monroe and State of New York, have invented a new, original, and ornamental Design for A Combined Cigarette Holder and Ash Tray of which the following is a specification, reference being had to the accompanying drawings, forming a part thereof.

In the drawings:

Figure 1 is a side elevation of a combined cigarette holder and ash tray, in the position in which it rests on a table and showing my new design;

Figure 2 is a side elevation thereof in the position in which it is held in the hand during use;

Figure 3 is an end view taken from the left of Figure 2;

Figure 4 is an end view taken from the right of Figure 2 and

Figure 5 is a top view of the Figure 2 position.

I claim:

The ornamental design for a combined cigarette holder and ash tray, as shown.

CARL G. JOHNSON.
